THEODORE H. WOBERMIN, OF WHITTIER, CALIFORNIA.

WELL SWAB.

Application filed January 3, 1927. Serial No. 158,576.

This invention relates to a swab for wells, such as oil wells, wherein the lifting hold is effected by means of a valve. The present invention pertains more particularly to a swab having an expansible annulus serving as a packing. Such annulus are commonly made of rubber and are subject to excessive wear by reason of their fixed position on the swab body or mandrel. The provision of a valve port opening of sufficient size for efficient operation of the swab is another problem, encountered in such devices. A further desideratum is a swab which may be unloaded.

15 The objects of this invention are first, to provide a swab having an annulus mounted on a tubular mandrel so it may have a limited longitudinal movement and a free rotary movement; second, to provide a swab having a sleeve valve operable by movement of the annulus; third, to provide a swab having an annulus adapted to accommodate itself to the casing upon the upward stroke thereof; and fourth, to provide a swab which may be unloaded.

20 These objects, together with other objects and corresponding accomplishments are obtained by means of the embodiment of my invention illustrated in the accompanying drawing, in which:

25 Fig. 1 is an axial section through a complete swab; and Figs. 2, 3, and 4 are sections as seen on the lines correspondingly numbered in Fig. 1.

30 Referring with more particularity to the drawing, 5 indicates a mandrel of tubular form, there being a bore 6 extending therethrough to an enlarged portion 7. There are laterally extending passages, 8 which

35 connect the bore 6 with the outside of the head. Valve ports 9 connect the bore to the outside at the lower end, and the mandrel is externally threaded as indicated by 10 to receive end piece. A tapered threaded pin

40 11 is provided at the top of the mandrel for connection to a swab string. Laterally extending ducts 12 communicate with the bore for the purpose of admitting fluid to be elevated such as oil to an annular space

45 around the mandrel, later described.

An end piece 13 with torpedo shaped point to pass through the fluid with little resistance is secured to the mandrel and closes the bore at the lower end. Mounted

50 on the mandrel above the end piece is a shouldered ring 14 supporting a washer 15

55 just below the ports 9. Mounted so as to be longitudinally slideable upon the mandrel is a supporting member 16. It is provided with a cupped portion to receive an end 60 of the swab rubber. Resting on the shoulder of ring 14 and engaging a shoulder on the supporting member 16, is a compression spring 17.

65 The well swab packing member comprises a tubular member preferably of rubber of largest external diameter at the center and having two face portions 19 and 20. The inclination or pitch of the lower face 19 is less than the upper face. There is also a 70 tubular extension or thimble defined by a shoulder 21, the tubular extension being of such dimensions that it will fit within the supporting member 16, the face of portion 19 of the rubber merging with the external 75 wall of the supporting member as best shown in Fig. 1. There is a substantially cylindrical bore extending through the annulus or packing member, this bore being lined by bushing sleeves 22 and 23, which 80 are spaced from one another so as to form an annular pressure recess 24 at about the center of the rubber. The ducts 12 register at all times with the space 24 placing the latter in communication with the bore of the mandrel.

85 Slidably mounted upon the part 5 of the mandrel is an upper supporting member 25 receiving the upper end of the swab rubber and arranged to abut the shoulder 26 on the 90 body. The member 25 is formed with an external shoulder to serve as a seat for a compression spring 27.

95 The construction is such that the swab rubber floats longitudinally and rotatably on the mandrel, being supported at the ends by compression springs 17 and 27. In many swabs which have been constructed, there has been a swivel connection between the swab string and the mandrel in order to 100 permit the swab to turn and accommodate itself to the casing during its movement into the casing and when lifted. It is also apparent that the swab may be expanded by being swelled outwardly. The rubber is 105 pear shaped being thicker at its lower portion so that excessive deformation and consequent damage upon expansion are precluded; the greatest wear also coming on this thicker portion.

110 The annulus acts as a sleeve member of a sleeve valve. If the annulus is moved

55

downwardly a sufficient distance, the sleeve 22 will cover the ports 9 and close the bore 6 from communication with the space below the swab rubber. Normally, the ports, 6 are in the position shown in Fig. 1. In this condition, the swab may be lowered in the casing.

The rubber at its greatest diameter is slightly smaller than the casing in which 10 the swab is to run, permitting it to be easily lowered and eliminating wear on the rubber on the down stroke. Oil which is within the casing is free to pass through ports 9 into the bore 6 and through the ports 8 thereby allowing free movement of the swab 15 downwardly. To exert a lift, the swab is suddenly pulled upwardly. This causes a pressure upon the upper part of the annulus and it is moved downwardly upon the mandrel so that sleeve 22 closes ports 9. The 20 pressure of the column of oil above the swab is then exerted and transmitted through the ducts 12 to the space 24, and together with the suction created below and the weight of 25 the column of oil above causes an expansion of the swab rubber and a tight fit against the casing so that the swab is able to perform its work. In the expansion of the rubber, the face 19 comes in contact with the well 30 casing and the wear is taken by the rubber at this locality. It will be noted that the portion of the rubber having the greatest amount of stock is at this place in the annulus. The rubber has a long life. It also 35 will be noted that when the swab rubber together with its supporting member 16 is moved downwardly it will close ports 9 and also seat upon the washer 15, thereby serving as a double seal. The size of the ports 40 9 may be made as large in cross section as desired by lengthening the mandrel.

An important feature in the operation of the swab is that it may be unloaded, it being possible to make it discharge any or all of 45 the fluid held above it at any desired point in the upward stroke. This may be readily accomplished by suddenly arresting the upward progress of the swab; this will in effect be a jerk and will cause the annulus to raise, 50 due to its inertia and the floating action of springs 17 and 27 and open ports 9, permitting the fluid to escape. If desired, these ports may be closed again as at the beginning of another stroke. Unloading is necessary 55 at such times as the swab picks up a load too heavy for the derrick machinery to raise, and obviates the danger of leaving the string in the hole. It is also an advantage when it is desired to surge a well, as it eliminates 60 the necessity of bringing the swab to the surface at every stroke, permitting instead a short stroke of possibly one-hundred or two-hundred feet or whatever is desired.

What I claim is:

65 1. A well swab comprising a body having

a tubular mandrel portion, an annulus of resilient material mounted on said mandrel portion so as to be slidably longitudinally and rotatably, said mandrel portion having lateral ports at the lower end so located that 70 said annulus may be moved downwardly to close said ports and form a sleeve valve, and spring means tending to float said annulus on said mandrel above said ports.

2. A well swab comprising a body having 75 a tubular mandrel portion, an annulus of resilient material slidably mounted on said mandrel portion and floated thereon, there being a pressure space between the annulus and mandrel portion communicating with the bore of said mandrel portion and passages in said body placing the bore of said mandrel in communication with the exterior above said annulus, said mandrel portion having lateral ports at the lower end so located that said annulus is normally floated to uncover and may be moved downwardly to close said ports and form a sleeve valve.

3. A well swab comprising a body having 80 a tubular mandrel portion, an annulus of resilient material mounted on said mandrel portion so as to be slidably longitudinally and rotatably, there being a pressure space between the annulus and mandrel portion communicating with the bore of said mandrel portion and passages in said body placing the bore of said mandrel portion in communication with the exterior above said annulus, said mandrel portion having lateral ports at the lower end so located that said annulus may be moved downwardly to close said ports and form a sleeve valve, and means tending to float said annulus on said mandrel above said ports.

4. A well swab comprising a body having 85 a tubular mandrel portion, a packing annulus mounted on said mandrel portion so as to be slidably longitudinally, said mandrel portion having lateral ports at the lower end so located that said annulus may be moved downwardly to close said ports and form a sleeve valve, and springs supporting said annulus on said mandrel portion so as to float it above said ports.

5. A well swab comprising a body having a 90 tubular mandrel portion, an annulus of rubber having peripheral faces tapering from an intermediate portion toward the ends and provided with a substantially cylindrical bore, said annulus being floated on said tubular portion of said mandrel so as to be rotatably and longitudinally slidably, there being a pressure space between the annulus and mandrel portion communicating with the bore of said mandrel portion and passages in said body placing the bore of said mandrel portion in communication with the exterior above said annulus, said mandrel portion having lateral ports at the lower end so located that said annulus may be 95 100 105 110 115 120 125 130

moved downwardly to close said ports and form a sleeve valve.

6. A well swab comprising a body having a tubular mandrel portion, an annulus of rubber having peripheral faces tapering from an intermediate portion toward the ends and provided with a substantially cylindrical bore, said annulus being mounted on the tubular portion of said mandrel so as to be rotatably and longitudinally slideable, there being a pressure space between the annulus and mandrel portion communicating with the bore of said mandrel portion and passages in said body placing the bore of said mandrel portion in communication with the exterior above said annulus, said mandrel portion having lateral ports at one end so located that said annulus and said mandrel portion form a sleeve valve and spring means tending to float said annulus on said mandrel above said ports.

7. A well swab comprising a body having a tubular mandrel portion, an annulus of rubber having peripheral faces tapering from an intermediate portion toward the ends and provided with a substantially cylindrical bore the pitch of the lower portion of said annulus being less than the pitch of the upper portion, said annulus being floated on the tubular portion of said mandrel so as to be rotatably and longitudinally slideable, there being a pressure space between the annulus and mandrel portion communicating with the bore of said mandrel and passages placing the bore of said mandrel portion in communication with exterior above said annulus, said mandrel portion having lateral ports at the lower end so located that said annulus may be moved downwardly to close the ports and form a sleeve valve with said mandrel portion.

8. A well swab comprising a body having a tubular mandrel portion, an annulus of rubber having peripheral faces tapering from an intermediate portion toward the ends and provided with a substantially cylindrical bore, and spaced sleeves in the bore of said annulus forming a liner with an intermediate pressure space, said annulus being floated on said mandrel so as to be rotatable and slideable longitudinally there being passages in said body placing the bore of said mandrel portion in communication with said pressure space and passages in said body placing the bore of said mandrel portion in communication with the exterior above the said annulus, said mandrel portion having lateral ports at the lower end so located that said annulus may be moved downwardly to close said ports and form a sleeve valve.

9. A well swab comprising a body having a tubular mandrel portion, an annulus of rubber having peripheral faces tapering from an intermediate portion toward the

ends and provided with a cylindrical bore, spaced sleeves in the bore of said annulus forming a liner with an intermediate pressure space, said annulus being floated on said mandrel portion so as to be rotatably and longitudinally slideable, there being passages in said mandrel portion communicating with the bore thereof and passages in said body placing the bore of said mandrel portion in communication with the exterior above said annulus, said mandrel portion having lateral ports at the lower end so located that said annulus may be moved downwardly to close said ports and form a sleeve valve, and spring means tending to float said annulus on said mandrel portion above said ports.

10. A well swab comprising a body having a tubular mandrel portion, an enlargement on said body at the upper end forming a head, the lower end being of enlarged diameter and forming a head with an intermediate cylindrical portion between said heads, an annulus of rubber mounted on said mandrel portion so as to be rotatably and longitudinally slideable, there being a pressure space between the annulus and mandrel portion communicating with the bore of said mandrel portion and passages in said body placing the bore of said mandrel portion in communication with the exterior above said annulus, said mandrel portion having lateral ports at the lower end so located that said annulus may be moved downwardly to close said ports and form a sleeve valve, a compression spring disposed between the lower head and said annulus to provide spring means floating said annulus on said mandrel above said ports.

11. A well swab comprising a body having an enlargement at the upper end forming a head, a lower end of enlarged diameter detachably mounted on said body whereby to provide an intermediate cylindrical mandrel portion, an annulus of rubber having peripheral faces tapering from an intermediate portion towards the ends, said annulus being mounted on the cylindrical portion of said body so as to be rotatable and longitudinally slideable; supporting means mounted over the ends of said annulus, there being a pressure space between the annulus and cylindrical portion communicating with the bore of said cylindrical portion and passages in said body placing the bore of said cylindrical portion in communication with the exterior above said annulus, said cylindrical portion having lateral ports at the lower end so located that said annulus may be moved downwardly to close said ports and form a sleeve valve, a compression spring disposed about the cylindrical portion of said body between the upper head and the upper supporting member, a compression spring disposed about the cylindrical portion

of said body between the lower head and the lower supporting member so as to float said annulus on said mandrel above said ports.

12. A well swab comprising a body having an enlargement thereon at the upper end forming a head and a detachable lower end of enlarged diameter providing a head with an intermediate cylindrical portion between said heads, an annulus of rubber having peripheral faces tapering from an intermediate portion towards the ends and provided with a substantially cylindrical bore, the pitch of the face at the upper end being greater than the pitch of the face at the lower end, supporting means mounted upon the ends of said annulus, spaced sleeves in the bore of said annulus forming a liner with an intermediate pressure space, said annulus being mounted on the cylindrical portion of said body so as to be rotatably and longitudinally slidable, there being passages connecting the bore of said cylindrical portion with said pressure space and passages in said body placing the bore of said cylindrical portion in communication with the exterior above said annulus, said cylindrical portion having lateral ports at the lower ends so located that said annulus may be moved downwardly to close said ports and form a sleeve valve, a compression spring mounted about said cylindrical portion between the upper head and the upper sup-

porting member, a compression spring mounted about the cylindrical portion of said body between said lower supporting member and said lower head thereby providing spring means tending to float said annulus on said mandrel portion.

13. A well swab comprising a body having a packing member expansible by fluid pressure from above said swab, and a tubular mandrel arranged for passage of fluid therethrough and having lateral ports, a sleeve mounted to float on said mandrel with said ports normally opened thereby providing a sleeve valve for controlling the passage of fluid through said swab.

14. A well swab comprising a body having a tubular mandrel portion arranged for the passage of fluid therethrough, a packing member including an annulus of resilient material slidably mounted on said mandrel portion and expansible by fluid pressure from above said swab, there being ports at the lower end of said mandrel portion so located that said packing member may be moved downwardly to close said ports and form a sleeve valve, said packing member being floated on said mandrel portion so that said ports are normally open.

In witness that I claim the foregoing I have hereunto subscribed my name this 27th day of October, 1926.

THEADORE H. WOBERMIN.
